Primary Examiner—Marcus A. Jackson*Attorney, Agent, or Firm*—Evenson, McKeown, Edwards & Lenahan, P.L.L.C.[57] **CLAIM**

The ornamental design for a vehicle body member with receptacle for brake lights, as shown and described.

DESCRIPTION

FIG. 1 is a left-rear perspective view of a vehicle body member with receptacle for brake lights according to my novel design shown for illustrative purposes on a rear end of vehicle;

FIG. 2 is a rear view of the vehicle body member of FIG. 1;
FIG. 3 is a left-rear perspective view from above of the vehicle body member of FIG. 1;

FIG. 4 is a left-front perspective view from above of the vehicle body member of FIG. 1;

FIG. 5 is a front view from above of the vehicle body member of FIG. 1;

FIG. 6 is perspective left side view from above of the vehicle body member of FIG. 1;

FIG. 7 is a front perspective view from below of the vehicle body member of FIG. 1;

FIG. 8 is a rear perspective view from below of the vehicle body member of FIG. 1; and,

FIG. 9 is a perspective side view from below of the vehicle body member of FIG. 1.

The broken line showing in FIG. 1 is for illustrative purposes only to indicate the environmental structure and forms no part of the claimed design.
